Primary Examiner — Wan Laymon*Assistant Examiner* — Clint A Samuel(74) Attorney, Agent, or Firm — Dilworth Paxson LLP; Edward F. Behm, Jr.(57) CLAIM

The ornamental design for a leotard, as shown and described.

DESCRIPTION

FIG. 1 is a perspective view of a leotard.

FIG. 2 is a front plan view thereof.

FIG. 3 is a back plan view thereof.

FIG. 4 is a left view thereof.

FIG. 5 is a right view thereof.

FIG. 6 is a top view thereof; and,

FIG. 7 is a bottom view thereof.

The broken lines shown in the drawings are included for the purpose of illustrating portions of a leotard and form no part of the claimed design.
